DESIGN FOR A DRESS ENSEMBLE

Vivian Amen, New York, N. Y.

Application September 9, 1940, Serial No. 94,877

Term of patent 3½ years

To all whom it may concern:

Be it known that I, Vivian Amen, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design, and

Fig. 2 is the rear view of the dress ensemble.

Fig. 3 is a fragmentary front view of the dress member of the ensemble, and

Fig. 4 is a fragmentary rear view thereof.

The characteristic feature of my design resides in the combination on the ensemble disclosed of the specific, open-front, collarless jacket member having deep front and rear yokes, and the disclosed button arrangement on the front yoke and waistband, in association with the specific two-toned shirtwaist dress as shown.

I claim:

The ornamental design for a dress ensemble, substantially as shown and described.

VIVIAN AMEN.
